UNITED STATES PATENT OFFICE.

JAMES D. FRANKLIN, OF CHATTANOOGA, TENNESSEE.

WRENCH.

Application filed March 20, 1923. Serial No. 626,326.

To all whom it may concern:

Be it known that JAMES D. FRANKLIN, a citizen of the United States, residing at Chattanooga, in the county of Hamilton and State of Tennessee, has invented certain new and useful Improvements in Wrenches, of which the following is a specification.

This invention relates to a wrench and has for its principal object to provide a device which will efficiently and more easily be adjusted for use in conjunction with removing or tightening nuts upon bolts or the like and furthermore in connection with the turning of a pipe.

Another important object of the invention is to provide a wrench of the above mentioned character which may be converted from the usual type wrench known in the art as a monkey wrench to a pipe wrench.

Another important object of the invention is to provide a wrench of the above mentioned character, which is of such a construction as to enable the same to be adjusted to various sizes.

A still further object is to provide a wrench which is simple in construction, inexpensive, strong, durable, and further, well adapted for the purposes for which it is designated.

Other objects and advantages of this invention will become apparent during the course of the following description.

In the accompanying drawings forming a part of this specification and in which like numerals designate like parts throughout the same:

Figure 1 is a front elevation of my improved wrench.

Figure 2 is a side elevation of the same.

Figure 3 is a sectional view taken on line 3—3 of Fig. 1 and looking in the direction of the arrows.

Figure 4 is a sectional view taken on line 4—4 of Fig. 1.

Figure 5 is a detail front elevation of a modification of a jaw construction which is adapted for use in connection with the turning of pipes.

Figure 6 is a side elevation of the modification.

Figure 7 is a section taken on line 7—7 of Fig. 6.

In the drawings wherein for the purpose of illustration is shown the preferred embodiment of my invention, the numeral 1

designates the shank of my improved wrench the shank being provided at its upper end with the stationary jaw 2. The stationary jaw 2 is provided with the inner flat face 3 which is adapted to cooperate with the inner flat face 4 of the slidable jaw 5 which is slidably carried by the shank 1.

The slidable jaw 5 is provided with a recessed portion 6 adjacent the lower inner end and a pin 7 extends transversely across the jaw 5 within the recess 6. The purpose of this recess 6 and the transverse pin 7 is to provide a means for pivotally supporting the upper end of the rack bar 8 in the jaw 5 as more clearly shown in Fig. 1 of the drawings. The rack bar 8 is provided with the transversely extending teeth 9 in the outer side edge and this rack bar 8 is adapted to extend downwardly from the slidable jaw 5 adjacent the shank 1.

Pivotedly mounted on the shank 1 at a point adjacent the intermediate portion thereof is the bracket designated by the numeral 10 generally. This bracket 10 comprises a pair of like plates 11 and 12 respectively and these plates are mounted on the pivot 13 on the front and rear faces of the shank 1 intermediate their ends. Adjacent the inner ends of the plates 11 and 12 and extending transversely therebetween is the dog or catch 14. The catch or dog 14 is adapted to engage the teeth 9 provided in the rack bar 8 and the lower end or free end of the rack bar 8 is adapted to pass through the bracket 10 between the plates 11 and 12 thereof and in the manner more clearly shown in Figs. 1 and 3 of the drawings.

To normally keep the rack bar 8 in engagement with the dog 14 I provide a flat spring 15, the lower end of which is secured to the shank 1 as at 16 in the drawings, the upper free end of the spring 15 being adapted to rest against the inner side face of the rack bar 8 as more clearly shown in the drawings. A lever 17 has its upper end reduced to provide shoulders 18 and 19 respectively and the purpose of this construction is to enable the upper end of the lever 17 to be disposed between the outer free ends of the plates 11 and 12. The plates 11 and 12 have their outer ends adapted to rest on the shoulders 18 and 19 provided in the upper end of the lever 17 and a suitable pin or bolt 20 is adapted to pass through the plates 11

and 12 and the upper reduced portion of the handle 17 whereby the lever 17 is held in a locked position with respect to the bracket 10 and furthermore will enable the bracket 10 to be operated upon movement of the lever 17 as will be more fully described hereinafter.

The shank 1 is provided with a threaded aperture which extends transversely from the inner side face to the outer side face of the shank and is adapted to receive therein the threaded adjusting screw 22. The purpose of this adjusting screw 22 is to enable the screw to be turned so that the free end of the screw will extend beyond the outer side face of the shank 1 for engagement with the inner side face of the lever 17 whereby the inward movement of the lever is limited.

With the parts adjusted as shown in the full lines in Fig. 1 of the drawings, the sliding jaw 5 is moved upon the shank to cooperate with the stationary jaw 2 and after the jaw 5 has been adjusted to the proper size and position by moving the rack bar 8 away from engagement with the dog 14 and against the tension of the spring 15, the lever 17 is then moved inwardly to the dotted lines in the position as shown in Fig. 1 of the drawings whereby the dog 14 will be caused to engage the tooth in the rack bar 8 adjacent the dog whereby the sliding jaw 5 will be caused to bind against the nut or object held between the stationary jaw and the sliding jaw whereby the sliding jaw is brought into a locked position and by grasping the lever 17 with the shank 1 the jaws are held in locked engagement with the object and the wrench is then in position to be operated. To release the wrench from engagement with the object when the same has been turned, it is always necessary to move the rack bar 8 inwardly against the tension of the spring 15 and out of engagement with the dog 14 whereby the sliding jaw 5 may be freely moved along the shank 1 and thereby released from engagement with the object with which it was locked.

In Figs. 5 and 6 of the drawings, I have shown a modification of jaw construction whereby the stationary jaw 2 and the sliding jaw 5 are adapted to receive the supplemental jaws 23 and 24 respectively. The purpose of these jaws is to provide a means whereby the wrench may be used in connection with turning pipes which could not be done with the flat inner faces 3 and 4 of the jaws 2 and 5 respectively. The jaw 23 is provided with a cutout portion 25 which is adapted to enable the jaw to fit over the shank 1 and is also provided with the socket portion in the upper face thereof as designated by the numeral 26 for the purpose of permitting the same to enclose the stationary jaw 2 as more clearly shown in Fig. 6 of the drawings. The jaw 23 is furthermore pro-

vided with a curved inner face and which is provided with the teeth or serrations 27. To further hold the jaw in position upon the stationary jaw 2, I provide the locking screw 28. This locking screw 28 is adapted to extend into the stationary jaw 2 whereby the supplemental jaw 23 may be held in its supported position upon the jaw 2.

The other supplemental jaw 24 is provided with a similar cutout portion 29 for the purpose of permitting the same to fit around the shank 1 and is also provided with the socket 30 whereby the same may enclose the sliding jaw 5. It will be noted from Fig. 6 of the drawings that the front face of the sliding jaw 5 is provided with a longitudinally extending groove or slot 31 and adapted to fit in this groove or slot 31 is the longitudinally extending tongue or rib 32 provided on the front face of the jaw 24. The inner face of the jaw 24 is provided with the serrations or teeth 33 which cooperate with the serrations or teeth 27 provided in the inner face of the jaw 23.

In use, when it is desired to use the wrench in connection with the turning of a pipe or the like, the supplemental jaws 23 and 24 are placed in their proper position upon the stationary jaw 2 and slideable jaw 5 respectively and the pipe is then placed between the serrated faces of the jaws 23 and 24 and the rack bar 8 is then moved into proper position whereby the jaw 24 which is carried by the slideable jaw 5 is brought into engagement with the pipe or other object disposed between the jaws 23 and 24 as heretofore described and by operating the lever 17 in the manner as hereinbefore set forth the jaw 24 will be caused to be brought into locking engagement with the pipe whereby the pipe is held in a locked position between the jaws and furthermore enable the wrench to operate the pipe in the desired manner.

It will thus be seen from the foregoing description that a wrench has been provided wherein the same may be easily changed from an ordinary type of monkey wrench to a pipe wrench and does not require the use of several additional parts or the taking of considerable time in adjusting the relative parts to their proper positions. Furthermore, the simplicity and arrangement of parts on my improved wrench are such as to give the same the proper adjustments and will positively move the elements to be operated upon by the wrench in a locked position whereby the proper operation is insured.

From the foregoing description of the construction of my improved apparatus, it will be seen that I have provided a simple, inexpensive and efficient means for carrying out the objects of the invention, and while I have particularly described the elements best adapted to perform the functions

set forth, it is obvious that various changes in form, proportion and in the minor details of construction may be resorted to, without departing from the spirit or sacrificing any 5 of the principles of the invention.

What I claim as new and desire to secure by Letters Patent is:—

In a wrench of the class described, comprising a shank having a fixed jaw at its 10 upper end, a slideable jaw carried on said shank, said slideable jaw being provided with a socket in its lower face, a rack bar pivoted at its upper end within the socket of said slideable jaw and suspended from the latter 15 adjacent one side edge of said shank, a bracket comprising a pair of parallel plates straddling said shank and pivoted thereto intermediate of its ends, a dog carried between the inner ends of the plates forming 20 said bracket and adapted to engage the teeth of said rack bar, a lever reduced at its upper

end and having said reduced end extended between and secured to the outer ends of the plates forming said bracket, the shoulders formed at the reduced end of said lever 25 abutting the lower edges of the plates forming said bracket to provide a secure connection therebetween, a leaf spring secured at its one end to the side edge of said shank and bowed to contact with the side edge 30 of the rack bar and normally retain the latter in engagement with said dog, said shank being provided with a threaded opening therein adjacent its lower end and a thumb screw extending through said threaded opening and adapted to have its end contact with the inner side edge of said lever to limit the inward movement of the latter, as and 35 for the purposes described.

In testimony whereof I affix my signature. 40

JAMES D. FRANKLIN.
